CONVERTIBLE LADDER

Kibbey W. Couse, Newark, N. J.

Application July 12, 1954, Serial No. 442,836

7 Claims. (Cl. 228—25)

2

inoperative collapsed condition, and parts being shown in section.

Figure 6 is an enlarged fragmentary side elevational view showing the top of the ladder of Figure 5, parts being broken away.

Figure 7 is a plan view looking from the top along the line 7—7 of Figure 5.

Figure 8 is an enlarged fragmentary side elevational view of the top of the side rails of the ladder of Figure 5, showing the first step in assembling the step ladder sections, parts being broken away.

Figures 9, 10 and 11 are fragmentary edge views of the ladder of Figure 14, showing steps in the assembling of the ladder sections, parts being broken away;

Figure 12 is a fragmentary edge view showing an overlapped joint between two adjacent ladder sections of the ladder of Figure 14, parts being broken away;

Figure 13 is an enlarged fragmentary front elevational view of a joint between two adjacent ladder sections of the ladder of Figure 14, parts being broken away;

Figure 14 is a front elevational view of a three section ladder forming an extension ladder embodying another form of my invention.

Figure 15 is an edge view thereof, showing in dot-dash lines the lower part of another ladder section in initial assembling position.

Figure 16 is an edge view of the ladder of Figure 14 shown in operative position against a supporting structure.

Figure 17 is a similar view of a single ladder section shown hooked over a support.

Referring in detail to the various views of the drawings and particularly to Figure 1, a ladder section made in accordance with the present invention is designated 1 and comprises two elongated stiles or side rails 2 and 3 having slanting steps or rungs 4 secured to and bridging the stiles or rails at regular intervals. The stiles or rails are formed of metal and are tubular in formation and square in cross-section, each stile including a front wall 5, a rear wall 6 and side walls 7. The steps 4 are formed of inverted channel-shaped metal bars fastened to the inner side walls 7 of the stiles by welding or in any other suitable manner.

According to the present invention, the ladder section 1 is provided with means for combining two such sections 45 in order to produce either a step ladder 8 such as shown in Figure 5 or combining two or more of such sections to produce an extension ladder 9 as shown in Figure 9. Such means includes a curved hook-like extension 10 projecting from the top end of stile or rail 2 and a curved hook-like extension 11 projecting from the top end of stile or rail 3. Extension 10 is in the form of an elongated metal tube having a straight portion 12 projecting into the top end of the rail 2 and a curved end portion 13 projecting outwardly of said top end. A square shaped plate 14 is sleeved over the straight portion 12 of the tube and welded to said portion adjacent its inner end. The plate is secured to the stile or rail 2 along its peripheral edge by welding or the like. A similar shaped plate 15 is similarly mounted and secured to the tube at the outer end of its straight portion 12 and is welded to the top end edge of the stile. The plates 14 and 15 hold the tube against twisting or bending in the side rail and plate 15 in addition serves as a closure for the top end of the side rail.

60 The extension 11 is similar in shape to the extension 10 with a straight portion 16 and a curved end portion 17 projecting outwardly of the stile or side rail 3 but is formed of solid metal rod. The extension 11 is arranged and secured to the stile or side rail 3 by means of plates 18 and 19 similar to the plates 14 and 15, respectively. The outside diameter of the curved portion 17 of the rod is such as to fit slidably in the curved portion 13 of the

The invention relates to ladder constructions and more particularly to new and useful improvements in a ladder capable of serving as a single flight ladder and adapted to be converted into a propped or step ladder or into an extension ladder.

In the ordinary ladder construction which is adapted to be converted into a step ladder or extension ladder, the ladder sections are unsure and shaky and it is necessary to provide safety grip sockets, safety catches, guide bands and other attachments which are cumbersome, apt to become accidentally detached or improperly attached, are expensive and need considerable skill to manipulate. Furthermore, in such ladder constructions the top or last step or rung is usually much too close to the supporting surface to permit secure foot and hand space.

A prime object of the present invention is to provide a ladder section which is complete in itself to serve as a single flight ladder but which is provided with means for detachably connecting another identical ladder section thereto to produce a rigid step ladder or for detachably connecting another identical ladder section or sections thereto to produce a rigid extension ladder.

Another object of the invention is to provide a ladder section adapted to be associated with another identical section to produce a step ladder or an extension without the necessity of the usual attachments for safety and guiding purposes.

A further object of the invention is to provide a ladder section adapted to be converted into a step ladder characterized by means for producing the proper safety angle of the supports for the step ladder.

Still another object of the invention is to provide a ladder construction with means for spacing the uppermost step or rung away from the vertical supporting surface in order to provide secure foot and hand space.

Other objects of the invention are to provide a ladder of this character which is simple in construction, characterized by fewness of parts, sturdy and rigid, readily assembled and disassembled and which can be manufactured and sold at reasonable cost.

For further comprehension of the invention and of the objects and advantages thereof, reference will be had to the following description and accompanying drawings, and to the appended claims in which the various novel features of the invention are more particularly set forth.

On the accompanying drawings forming a material part of the present disclosure:

Figure 1 is a front elevational view of a ladder construction embodying my invention.

Figure 2 is a vertical sectional view taken on the plane of the line 2—2 of Figure 1.

Figure 3 is a rear view thereof.

Figure 4 is a fragmentary perspective view of the top portion of the ladder construction of Figure 1, parts being broken away.

Figure 5 is a side elevational view of a two section ladder forming a step ladder embodying another form of the invention, the ladder being shown in dotted lines in

extension 10. A semi-cylindrical enlargement 20 is formed on the outer convex surface of the curved portion 17 and extends from the closure plate 19 outwardly a considerable distance forming a shoulder 21 at its outer end.

The stile or side rail 2 is also formed with an elongated slot 22 in its front wall 5 and with an elongated slot 23 in its rear wall 6 in line with the slot 22, the slots 22 and 23 being sufficiently wide to receive the curved portion 13 of the extension 10. Side rail 3 is also formed with an elongated slot 24 in its front wall 5 opposite the slot 22 and with an aligned slot 25 in its rear wall 6, said slots being sufficiently wide to receive the curved portion 17 of the extension 11. The slots are positioned a suitable distance above the bottom ends of the stiles or side rails in order to provide ample overlapping space for the side rails. The uppermost step 4 is spaced an equal distance from the tops of the extensions 10 and 11 and is formed with an extension which curves outwardly and upwardly to form a substantially V-shaped socket portion 26 extending the length of the step.

In order to produce a step ladder, such as the ladder 8 shown in Figure 5, two ladder sections 1 are associated or combined. This is accomplished by positioning the rear walls 6 of the stiles of the sections in opposed relation and inserting the solid curved rod portions 17 of the extensions 11 into the tubular curved portions 13 of the extensions 10 as shown in Figures 5 and 6. The inward movement of the curved rods 17 into the tubular curved portions 13 is limited by the shoulders 21 of the enlargements 20 engaging the end edges of the tubular curved portions as shown in Figure 6. When the curved portions of the extensions are thus in telescopic engagement, the ladder sections 1 will be fanned outwardly as shown in Figure 5 to a degree preferably 30° from the vertical. In order to prevent the ladder sections from spreading beyond the safety angle, the angle of the shoulder 21 on the enlargement 20 is fixed at 30° from the vertical as shown in Figures 5 and 6.

In order to provide the preferred 30° angle, the extension members 10 and 11 must be properly curved and to produce the proper arc the following method has been found satisfactory in practice. A normally straight length of tubular stock and a normally straight length of solid rod stock are bent at their centers into semi-circles. In order to determine the proper size of the semi-circles, a dimension approximating slightly more than four times the side width of a stile or side wall of the ladder section is taken as a center line diameter. The tubular stock and the rod stock are then cut so that each is equal to one-quarter of a complete circle. The original lengths of both the tube stock and rod stock must be such as to leave a proper length when bent and cut so as to allow a straight portion sufficiently long to be inserted into the top end of the side rail and supported therein. When thus dimensioned and the side rails 2 and 3 are placed vertically with their rear walls opposed as shown in Figure 8 and with their longitudinal axes in line with the axes of the tubes and rods, the outer end edges of the tubes and rods will abut each other, end to end, the end of one rod abutting the end of its adjacent receiving tube.

It will be seen that when two ladder sections 1 are thus associated or combined a step ladder is produced which needs no spread struts, safety catches or extra attachments of any kind, and which is sturdy, rigid, safe and portable. The step ladder may be almost completely folded and still retain its identity as a step ladder.

In order to produce an extension ladder, a ladder section 1 is used as a main or bottom section and another ladder section 1 or a plurality of such sections 1 are telescopically mounted on the main or bottom section and on each other. In the extension ladder illustrated in Figure 14, one ladder section 1 serves as a main or bottom section A and two such ladder sections serve as intermediate and upper auxiliary ladder sections B and

C, respectively. In assembling the ladder sections, the intermediate auxiliary section B is positioned so that the front walls of its side rails face the rear walls of the side rails of the main or bottom section A. The front flange or wall of the lowermost inverted channel-shaped step 4 of the intermediate auxiliary section B is inserted into the V-shaped socket portion 26 formed on the uppermost step 4 of the main or bottom ladder section A as viewed in Figures 9, 10 and 11 so that the curved extensions 10 and 11 or the main or bottom section A will point toward the front walls of the side rails of the intermediate auxiliary section B whereby when the side rails of the main and auxiliary sections are brought into contacting relation, the extensions 10 and 11 on the bottom section A will be in alignment with the slots in the auxiliary section B. The section B is then swung toward the main section A using the V-shaped socket portion 26 as a fulcrum until it is in telescopic alignment with the main section. The extensions 10 and 11 of the main section A will then pass through the slots 22 and 24 in the front walls 5 and through the slots 23 and 25 in the rear walls 6 of the auxiliary section B. When completely inserted, the free ends of the extensions 10 and 11 protrude slightly beyond the outer surface of the rear walls 6 of the side rails of the auxiliary section B. Cotter pins 27 extending through openings 28 formed in the protruding outer ends of the extensions 10 and 11 prevent withdrawal of the extensions and lock the main and auxiliary sections rigidly together as a unit. The diameters of the slots 23 and 25 in the rear walls 6 of the side rails through which the extensions 10 and 11 pass are only slightly larger than the diameters of the extensions 10 and 11 and less in diameter than the depth of the groove forming the socket portion 26. This prevents unseating or displacement of the front flange of the step 4 of the auxiliary section B in the socket portion 26 of the main section A and furthermore prevents accidental swinging of the main and auxiliary ladder sections away from each other.

The upper auxiliary ladder section C of the extension ladder 9 is similarly combined and associated with the intermediate auxiliary section B by similarly inserting the front flange or wall of the lowermost step 4 of said upper auxiliary section C into the V-shaped socket portion 26 of the intermediate auxiliary section B and swinging the extensions 10 and 11 of the section B through the slots in the walls of the side rails of the upper section C and rigidly fastening the sections together by the cotter pins 27.

If desired, the cotter pins 27 may be suspended from a flexible chain or the like attached to the adjacent side rail of the ladder section.

While three ladder sections 1 have been shown assembled to produce the extension ladder 9, it will be understood that any number of ladder sections 1 may be used to provide an extension ladder of the desired length, and the side rails of the ladder sections may be of unequal length if desired.

The extension ladder thus described is rigid and safe and needs none of the usual grip sockets, safety catches and guide bands.

In using the extension ladder, the extensions 10 and 11 may be hooked over a support 29 as shown in Figure 17, or their free outer ends may rest against a vertical support such as indicated at 30 in Figure 16 thereby spacing the upper end of the ladder away from such support and thus provide ample foot and hand space for the user.

Anti-skid devices may be mounted on the bottom ends 70 of the stiles or side rails of the ladder section 1 if desired.

The solid rod extension 11 of ladder section 1 may be provided with a pointed tip which will permit the ladder construction to be used in Alpine work or scaling walls. The improved ladder construction may also be 75 used in bridging crevasses and the like. Furthermore,

the curved extensions 10 and 11 may be formed with additional openings, adjacent their free outer ends to accommodate additional cotter pins as a safety feature.

While I have illustrated and described the preferred embodiments of my invention, it is to be understood that I do not limit myself to the precise constructions herein disclosed and the right is reserved to all changes and modifications coming within the scope of the invention as defined in the appended claims.

What I claim is:

1. A ladder convertible to provide a propped ladder or an extension ladder and comprising a main ladder section and an auxiliary ladder section, each section including side rails having steps secured thereto and bridging the same, curved extensions on the top ends of the side rails of the main section, curved extensions on the top ends of the side rails of the auxiliary section separably telescopically connectible to the curved extensions on the main section for use of the ladder as a propped ladder, the side rails of said auxiliary section adjacent their bottom ends having slots, the curved extensions of said main section being separably receivable in said slots when the ladder is used as an extension ladder, and means to secure the side rails of the ladder sections together when the ladder is used as an extension ladder including means carried by the curved extensions of the main section and coactive with said auxiliary section, and a part on a step of one of said main and auxiliary ladder sections cooperative with a part on a step of the other of said main and auxiliary ladder sections.

2. A ladder section for a convertible ladder comprising side rails having slots therethrough, steps bridging said rails at spaced intervals, at least one of said steps having a flange along one edge, curved extensions each on one rail at one end of the ladder section and separably insertable into one of said slots of a similar ladder section, one of said curved extensions being tubular to serve as a socket for the other extension of a similar ladder section, and an upwardly facing grooved extension on one step to receive said flange of a similar ladder section, whereby both said curved extensions and said flange of said ladder section may be inserted into said slots and said grooved extension respectively of another ladder section to provide an elongated straight ladder, and the second-mentioned extension of said ladder section may be inserted into the first-mentioned extension of a similar ladder section to provide a short step ladder.

3. A ladder section as defined in claim 2 with the addition of a stop on the first-mentioned curved extension of said ladder section to abut the end of the second-mentioned curved extension on a similar ladder section to limit movement of the ladder sections apart.

4. A convertible ladder comprising two ladder sections each including side rails having slots therethrough and steps bridging said rails at spaced intervals longitudinally of the rails, at least one of which steps has a depending flange, curved extensions on the rails at one end of one of said sections each separably insertable into one of said slots in the other section, one of said curved

extensions being tubular to serve as a socket for the other extension of the other ladder section, and an upwardly facing grooved extension on one step to receive said flange on the step of the other ladder extension, whereby both said extensions and said flange of one ladder section may be inserted into said slots and said grooved extension respectively of the other ladder section to provide an elongated straight ladder or the second-mentioned extension of each ladder section may be inserted into the first-mentioned curved extension of the other ladder section to provide a short propped ladder.

5. A convertible ladder as defined in claim 4 wherein the second-mentioned curved extension of each ladder section has an enlargement to abut the end of the tubular curved extension of the other ladder section and serve as a stop when the second-mentioned curved extension is inserted into the tubular curved extension.

6. A convertible ladder as defined in claim 4 with the addition of means separably connectible to the outer ends of the curved extensions of one ladder section to coact with the rails of the other ladder section to prevent pivotal movement of said ladder section about said flange and said grooved extension when the ladder sections are arranged to provide an elongated ladder.

7. A ladder section for a convertible ladder comprising side rails having slots therethrough, steps bridging said rails at spaced intervals, said section having a downwardly extending flange, curved extensions each on one rail at one end of the ladder section and separably insertable into one of said slots of a similar ladder section, one of said curved extensions being tubular to serve as a socket for the other extension of a similar ladder section, and an upwardly facing grooved extension to receive said flange of a similar ladder section, whereby both said curved extensions and said flange of said ladder section may be inserted into said slots and said grooved extension respectively of another ladder section to provide an elongated straight ladder, and the second-mentioned extension of said ladder section may be inserted into the first-mentioned extension of a similar ladder section to provide a short step ladder.
